UNITED STATES PATENT OFFICE.

DOUGLAS H. KING, OF IRVINGTON, NEW JERSEY; FRANCIS J. DOWD, OF BROOKLYN, NEW YORK, AND CHARLES W. STEVENS, OF ARLINGTON, NEW JERSEY, ASSIGNEES TO WESTERN ELECTRIC COMPANY, INCORPORATED, OF NEW YORK, N. Y., A CORPORATION OF NEW YORK.

SELECTOR SWITCH.

Application filed June 26, 1923. Serial No. 647,827.

The object of this invention is to provide an improved switch of simple and inexpensive construction for use in automatic telephone systems in various capacities, such as 5 a line finder, line switch or register.

A feature of this invention is an arrangement whereby the energy transmitted to the moving member of the switch is distributed more evenly by applying the motive power 10 to the shaft at a point midway between its supports.

Another feature is the provision of a bank of terminals with the contact segments placed upon the plane surfaces of the switch 15 bank whereby they are rendered readily accessible.

Other features will appear from the detailed description.

In the drawing:

20 Fig. 1 is a side view, and Fig. 2 a front view of a switch constructed in accordance with the invention. Fig. 3 is a view of the back stop, the stepping pawl, and the ratchet wheel. Fig. 4 is a sectional view of the 25 moulded bank showing the shape of the terminal punchings and the form in which they are assembled and Fig. 5 is a view of a section of the brush arm as shown at 5—5, Fig. 1.

30 Referring to the drawing, 1 indicates the main frame to which is secured by bolts 10, a moulded bank of terminals 3, (Fig. 4), semi-circular in formation. The opposite end of the bank 3 is secured by bolts 11 to an 35 angular piece of metal 2 of the frame. The moulded bank 3 consists of a plurality of terminals arranged in rows in the form of the arc of a circle, as shown in Fig. 1, there being preferably three rows of terminals on 40 each plane surface of the bank with the corresponding terminals of each row arranged in radial alignment. Each arcuate row contains as many terminals as are required. In the drawing, twenty sets of terminals are 45 shown, and assuming that six terminals are required for each trunk, such a switch would have an ultimate capacity of twenty trunks. Mounted on the free end 12 of the frame 1, is a shaft 13 which carries at each side of the 50 bank, a brush carrier 5. The carrier 5 has two sets of brushes 14. These sets of which one only is shown, are diametrically disposed for sweeping over the terminals on the right-

hand face (Fig. 1) of the bank 3, and two sets of brushes 15 (of which only one set is 55 shown) similarly disposed for sweeping over the terminals on the left-hand plane surface (not shown) of the bank 3. With this arrangement, it is apparent that during one complete revolution of the element 5, the 60 twin brush sets on each side will pass over the terminals of all the trunks in the bank. The twin brush sets 14 are electrically connected together, but are insulated from the twin brush sets 15, which are also electrically connected together. The brushes 14 are connected to the collector rings 16 by a plurality of leads 17 (Fig. 5), which are electrically connected to the brushes 18 to which, at their terminals 19, the brush leads 65 70 (not shown) may be attached.

The stepping magnet 4 is secured to frame 1 by a screw 20, and the armature of the magnet pivoted at 7 is extended by means of the arm 21 to the stepping pawl 22, held 75 in engagement with the teeth of the ratchet 23 by the tension of the spring 24, whose tension is regulated by the threaded pin 25 which is fitted with a lock nut 26. The end of the pawl 22 engages a stop 33 (Fig. 3) 80 to prevent the ratchet 23 and consequently the rotatable element 5, from stepping more than one contact at a time. The holding pawl 27 also secured to the frame 2, has one end in engagement with one of the 85 teeth of the ratchet 23, thus preventing the element 5 from rotating in a clockwise direction.

To make the stepping magnet 4 self-interrupting, the arm 21 in operating causes 90 the insulating cap 31 to force the contact spring 29 away from the contact member 30, thus opening the circuit of said magnet.

Assuming that a brush set on each plane surface of the bank is in engagement with the terminals of any trunk except the first or last, the other two brush sets will then be disengaged from the terminals in the bank. When the stepping magnet 4 is operated, 100 the brush sets will be rotated in a counter-clockwise direction by the operation of the stepping pawl 22 causing the brush sets to pass over the terminals of the bank in hunting for an idle trunk. If an idle trunk is not found before brush 14 breaks contact 105 with terminal 32, the brush arms will again

be stepped and the diametrically disposed brush 14 (not shown) will engage with the terminal 6 of the first line in the group and the magnet 4 will continue to operate and 5 rotate the brush arms step-by-step to hunt for an idle trunk in the bank. This cycle of operation continues until an idle trunk 10 is found. It will thus be seen that during element 5, the brush sets 14 and 15 will pass over the terminals of every trunk in the bank.

It is evident that because the ratchet is 15 mounted on the shaft midway between the brush carrying arms there is no lateral thrust when the magnet is energized and consequently more certain step-by-step movement of the brushes over the trunk terminals.

19 20 What is claimed is:

1. In a rotary switch, a semi-circular terminal bank having two parallel plane surfaces with terminals projecting from both of said surfaces, a brush shaft, two sets of rotatable brushes attached to said shaft for engaging said terminals, one set 25

engaging the terminals on one surface and the other set engaging the terminals on the other surface of the bank, a ratchet wheel located on said shaft between said brush sets, and a driving means for said ratchet mounted within the space enclosed by said brushes in their rotary movement.

2. In a rotary switch, a semi-circular terminal bank having two parallel plane surfaces with terminals projecting from both of said surfaces, a brush shaft, two sets of rotatable brushes attached to said shaft for engaging said terminals, one set engaging the terminals on one surface and the other set 35 engaging the terminals on the other surface of the bank, a ratchet wheel located on said shaft between said brush sets, and driving means cooperating with said ratchet and so located between said brush sets that it is 40 passed over by said sets in their rotation.

In witness whereof, we hereunto subscribe our names this 13th day of June, A. D., 1923.

DOUGLAS H. KING.
FRANCIS J. DOWD.
CHARLES W. STEVENS.
